(57) CLAIM

The ornamental design for a handbag, as shown and described.

DESCRIPTION

FIG. 1 is a front perspective view of a first embodiment of the handbag.

FIG. 2 is a front view of the handbag of FIG. 1.

FIG. 3 is a rear view of the handbag of FIG. 1.

FIG. 4 is a left side view of the handbag of FIG. 1.

FIG. 5 is a right side view of the handbag of FIG. 1.

FIG. 6 is a top view of the handbag of FIG. 1.

FIG. 7 is a bottom view of the handbag of FIG. 1.

FIG. 8 is a front perspective view of a second embodiment of the handbag.

FIG. 9 is a front view of the handbag of FIG. 8.

FIG. 10 is a rear view of the handbag of FIG. 8.

FIG. 11 is a left side view of the handbag of FIG. 8.

FIG. 12 is a right side view of the handbag of FIG. 8.

FIG. 13 is a top view of the handbag of FIG. 8; and, FIG. 14 is a bottom view of the handbag of FIG. 8.

The broken lines in the drawings represent stitching and form no part of the claimed design.

The solid black shading on the views of FIGS. 8–14 represents the color black.
